UNITED STATES PATENT OFFICE

HANS NEUBERT, OF ANNABERG, GERMANY, ASSIGNOR TO GENERAL ELECTRIC COMPANY, A CORPORATION OF NEW YORK

ELECTRICAL CONNECTER

Application filed July 15, 1927, Serial No. 206,060, and in Germany November 26, 1926.

My invention relates to electrical connectors, more particularly to detachable plug connectors such as are used with electric heating and cooking devices, and has for its object the provision of a simple, reliable and efficient means of this character which operates at a reduced temperature.

The contact devices of heating and cooking utensils in operation often attain such high temperature that the insulation of the conductor cords is damaged. According to this invention this disadvantage is obviated by reducing, as far as possible, the temperature at the connecting clamp of the feed conductor, which is effected by a great reduction of temperature within the connecting device itself. This reduction in temperature in the connecting device is in fact attained by making the connection between the utensil in operation and the feed conductor of a material which is a poor heat conductor, such as steel, chrome-nickel, constantan, German silver or the like. The decrease in the temperature can be still further increased by employing band-shaped feed conductors between the socket and clamp and also by using perforated socket housings.

For a more complete understanding of my invention reference should be had to the accompanying drawing; Fig. 1 of which is a sectional view of a connector plug embodying my invention; while Fig. 2 is a fragmentary side elevation view showing a conducting part of Fig. 1.

Referring to the drawing showing one embodiment of the invention, the contact socket housing 10, made of a suitable electrically insulating material, is attached to a flexible, insulated twin feed conductor 11 by means of contact clamps 12 carried by the housing, which also carries at its lower end the plug sockets 13 adapted to fit on contact pins carried by the utensil to be operated. According to the invention these plug sockets 13, and also the feed conductors 14 electrically connecting the plug sockets 13 and the contact lamps 12, are made of a material which is a poor heat conductor, such as steel, chrome-nickel, constantan, German silver or the like. Furthermore, the feed conductors

14 may consist of thin bands possessing but slight heat capacity and, at the same time, a comparatively great area. The invention is not restricted to plug devices only but can also be embodied in a proper sense for connections with screw contacts.

What I claim as new and desire to secure by Letters Patent of the United States, is:—

1. A connector for electric heating devices, comprising a support, electrical contacts carried by said support, electrically conducting leads extending into said support, and electrical conductors connecting said contacts and said leads made of material having poor heat conductivity.

2. A plug connector comprising an insulating support, a pair of plug contacts carried at one end of said support, a pair of clamps carried by said support adjacent the opposite end thereof, and electrical conductors connecting said contacts and said clamps made of a material having poor heat conductivity.

3. A plug connector comprising an insulating support, a pair of plug contacts carried at one end of said support, a pair of clamps carried by said support adjacent the opposite end thereof, and electrical conductors of band form connecting said contacts and said clamps, said conductors being made of a material having poor heat conductivity.

In witness whereof, I have hereunto set my hand this 11th day of June, 1927.

HANS NEUBERT.
